(57) **CLAIM**

We claim the ornamental design for the brush for vacuum cleaner, as shown and described.

DESCRIPTION

FIG. 1 is the front perspective view of the brush for vacuum cleaner showing our new design;
 FIG. 2 is the front view thereof;
 FIG. 3 is the rear view thereof;
 FIG. 4 is the left-side view thereof;
 FIG. 5 is the right-side view thereof;
 FIG. 6 is the top plan view thereof; and,
 FIG. 7 is the bottom plan view thereof.

The broken lines in the drawing show unclaimed environment only and form no part of the claimed design.
